UNITED STATES PATENT OFFICE.

FREDERICK J. ASH, OF PHOENIXVILLE, PENNSYLVANIA.

STOCKING-HOLDING DEVICE.

1,365,445.

Specification of Letters Patent.

Patented Jan. 11, 1921.

Application filed September 18, 1920. Serial No. 411,168.

To all whom it may concern:

Be it known that I, FREDERICK J. ASH, a citizen of the United States, residing at Phoenixville, in the county of Chester and State of Pennsylvania, have invented certain new and useful Improvements in Stocking-Holding Devices, of which the following is a specification.

One object of my invention is to provide improved means for holding a stocking on a drying form so as to prevent the stocking from creeping or shrinking while being dried upon said form.

Another object is to further improve on the structure covered in my United States Patent, No. 1,348,922 of August 10, 1920.

These objects, and other advantageous ends which will be described hereinafter, I attain in the following manner, reference being had to the accompanying drawings in which—

Figure 1 is a side elevation illustrating my improved structure in an inoperative position,

Fig. 2 is a fragmentary elevation showing my improved device in an operative position,

Fig. 3 is a fragmentary face view illustrating my present invention,

Fig. 4 is a fragmentary face view showing a slight modification of the form of my invention shown in Figs. 1 to 3 inclusive, and

Fig. 5 is a side view of Fig. 4.

In Figs. 1 and 2 of the drawing, I have illustrated my improved clamping jaws in combination with the actuating structure such as covered in my above mentioned U. S. patent; it being noted that I have found that by pivotally connecting the jaws to actuating arms so that the jaws when brought into engagement with the stocking on the form may swing or move to such extent as to accommodate themselves to the contour of the form with the stocking thereon.

Specifically in my present invention I provide jaws 6 in the form of perforated plates which have oppositely projecting forked lugs 7 as shown in Figs. 1, 2 and 3 and between the forks of these lugs, I pivotally connect the upper ends of arms 8 by pivot pins 9 so that when the arms are moved together on their pivot 6^b to clamp a stocking, such as the stocking 10 upon the drying form 11, the jaws are free to slightly move on their pivots 9 to accommodate

themselves to the contour of the stocking while on the form and so as to firmly and evenly press the stocking against the form and hold it against creeping lengthwise on the form during the drying action.

In Figs. 4 and 5 I have shown a construction in which the perforated jaws 6^a have projecting lugs 7^a which fit between forked ends 8^a of the arms 8. Pivot pins 6^a extend through the parts 8^a and lugs 7^a and thereby pivotally secure the jaws 6^a to the arms. In order to prevent accidental pivotal movement of the jaws I provide the spring 12 which is made in the form of a loop having its free ends 13 embracing the lug 7^a between the pivot and the jaw; said spring being secured by a screw 14 to a cross bar 15 on the upper end of the part 8^a of the arm 8. In this form of my invention while the jaws are free to swing on the pivots when they engage the stocking on the form, they are held against accidental movement and also in a predetermined normal position by means of the spring 12; thus insuring that the jaws be always presented to the stocking on the form without chance of accidental vibration during the applying movement of the jaws to the stocking.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A device of the character described including arms adapted to be moved toward and from a stocking drying form; and clamping jaws for engagement with a stocking on said form, said jaws being pivotally connected to said arms; substantially as described.

2. A device of the character described including arms adapted to be moved toward and from a stocking drying form; and clamping jaws for engagement with a stocking on said form, said jaws having lugs thereon pivotally connected to said arms; substantially as described.

3. A device of the character described

including arms adapted to be moved toward and from a stocking drying form; clamping jaws for engagement with a stocking on said form, said jaws being pivotally connected to 5 said arms; and resilient means for normally preventing accidental movement of said jaws on their pivots; substantially as described.

In testimony whereof I have signed my name to this specification in the presence of 10 two subscribing witnesses.

FREDERICK J. ASH.
